UNITED STATES PATENT OFFICE.

WILLIAM G. SHERER, OF CHICAGO, ILLINOIS.

DESIGN FOR A DRAWER-PULL.

50,040.

Specification for Design.

Patented Dec. 12, 1916.

Application filed September 5, 1916. Serial No. 118,583. Term of patent 14 years.

To all whom it may concern:

Be it known that I, WILLIAM G. SHERER, a citizen of the United States, residing at Chicago, in the county of Cook and State of Illinois, have invented a new, original, and ornamental Design for Drawer-Pulls, of which the following is a specification, reference being had to the accompanying drawings, forming part thereof, wherein—

Figure 1 is a front elevation; Fig. 2 is an

end elevation of the drawer pull illustrating my new design.

I claim:

The ornamental design for drawer pull as shown.

WILLIAM G. SHERER.

Witnesses:

LAUREL M. DOREMUS,
MARION INGRAHAM.
